DESIGN FOR A COMBINED SYNCHRONIZER AND SHUTTER TESTER

Robert L. Pennock, Jr., Denver, Colo.

Application November 7, 1946, Serial No. 134,601

Term of patent 14 years

(CL. D61—1)

To all whom it may concern:

Be it known that I, Robert L. Pennock, Jr., a citizen of the United States, residing at Denver, in the county of Denver and State of Colorado, have invented a new, original, and ornamental Design for Combined Synchronizer and Shutter Tester, of which the following is a specification, reference being made to the accompanying drawing, forming a part thereof.

In the drawings Figure 1 is a perspective view of a combined synchronizer and shutter tester, showing my new design with the top cover elevated; and Fig. 2 is a perspective view taken from the opposite side to the side shown in Fig. 1 with the cover in a closed position.

I claim:

The ornamental design for a combined synchronizer and shutter tester, as shown.

ROBERT L. PENNOCK, JR.
